* cited by examiner

Primary Examiner — Omeed Agilee(74) *Attorney, Agent, or Firm* — Muncy, Geissler, Olds & Lowe, P.C.(57) **CLAIM**

The ornamental design for a specimen collecting device, as shown and described.

DESCRIPTION

FIG. 1 is a top plan view of a specimen collecting device showing my new design;

FIG. 2 is a bottom plan view thereof;

FIG. 3 is a left side view thereof;

FIG. 4 is a right side view thereof;

FIG. 5 is a front elevational view thereof;

FIG. 6 is a rear elevational view thereof;

FIG. 7 is a perspective view thereof; and,

FIG. 8 is another perspective view thereof.

The broken lines in the drawings depict portions of the specimen collecting device that form no part of the claimed design.
